G. W. McCONNELL,
DEVICE FOR BALANCING PUMP RODS,
APPLICATION FILED MAY 14, 1917.

1,257,901.

Patented Feb. 26, 1918.

UNITED STATES PATENT OFFICE.

GEORGE W. McCONNELL, OF OKLAHOMA, OKLAHOMA, ASSIGNOR OF ONE-HALF TO W. B. McILWAIN, OF OKLAHOMA, OKLAHOMA.

DEVICE FOR BALANCING PUMP-RODS.

1,257,901.

Specification of Letters Patent. Patented Feb. 26, 1918.

Application filed May 14, 1917. Serial No. 168,580.

To all whom it may concern:

Be it known that I, GEORGE W. McCONNELL, a citizen of the United States, residing at Oklahoma city, in the county of Oklahoma and State of Oklahoma, have invented certain new and useful Improvements in Devices for Balancing Pump-Rods, of which the following is a specification, reference being had to the accompanying drawings.

This invention pertains to devices for balancing the weight or resistance of pump-rods in windmills.

An object of the invention is to produce a device of this kind which may be more easily and conveniently thrown into or out of gear or working relation with the pump-rod.

Other objects and advantages of the invention will be set forth in the ensuing description.

The accompanying drawings show one embodiment of the invention in actual practice.

Figure 1 is an elevation view showing the device in use on a windmill, the tower of the windmill being shown in section.

Fig. 2 is a reproduction of the lower portion of Fig. 1, but showing the device detached from the pump-rod.

Fig. 3 is a fragmental elevation view of parts shown in Fig. 1, but taken at right angles to Fig. 1.

Fig. 4 is an elevation view in the direction of the arrow 4 of Fig. 1, showing parts around and above the point indicated by said arrow.

Referring to the several figures, in all of which like characters of reference designate like parts, the numeral 5 designates the corner posts of a windmill tower; 6 the horizontal girt boards connecting said posts; and 7 the pump-rod of the windmill.

In carrying out the objects stated, a helical spring 8 is arranged to loosely embrace the pump-rod 7, and this spring is supported by rods 9 which attach to diametrically-opposite sides of its upper end and are themselves hooked over the girt boards 6 at their upper and outer ends as at 10.

At the points where these rods 9 attach to the spring 8, the coil of the latter is struck upward into a loop 11 to keep the rods from sliding around and pulling from wrong points.

Two hangers 12 are attached pivotally to

the lower end of the spring 8 to engage the pump-rod 7, and in order to connect these springs to the spring in a proper manner a sleeve 13 is screwthreaded up into the lower coils of the spring and loosely embraces said pump-rod, the hangers being pivoted to this sleeve.

The lower ends of the hangers 12 are adapted to be detachably connected to the pump-rod 7, and in arranging for this connection long strap-iron plates 14 are rigidly clamped to opposite faces of the pump-rod by bolts 15, the hangers being provided at their lower ends with spurs 16 adapted to engage holes 17 in said plates.

The lower ends of the hangers 12 are provided with hand-holds 18 so that they may be conveniently grasped to draw them downward.

When the hangers 12 are detached from the pump-rod, the latter is free to slide vertically through the sleeve 13 and not influenced by the spring 8, the hangers being held upward by the spring as shown in Fig. 2 where their spurs 16 will not hook into any of the holes 17 of the plates 14; but when it is desired to bring the spring into use in balancing the weight or resistance of the pump-rod it is stretched downward and placed under tension by taking hold of the hand-holds of the hangers and pulling the latter downward.

When the spring is under proper tension to balance the pump-rod 7, the hangers 12 are swung inward, bringing their spurs 16 into the nearest pair of holes 17 in the plates 14.

Having thus described the invention, I claim:

1. In a device of the class described, a helical spring adapted to embrace a pump-rod, means for suspending the spring, a hanger depending from the lower end of the spring, said hanger being provided with a spur adapted to engage a pump-rod.

2. In a device of the class described, a helical spring adapted to embrace a pump-rod, means for suspending the spring, a hanger depending from the lower end of the spring, said hanger having a spur, a plate adapted to be secured to the pump-rod and having holes to be engaged by said spur.

3. In a device of the class described, a helical spring adapted to embrace a pump-rod, means for suspending the spring, a

sleeve carried by the lower end of the spring and adapted to slidably embrace the pump-rod, a hanger depending from said sleeve, and means at the lower end of the hanger for detachably hitching said hanger to the pump-rod.

4. In a device of the class described, a helical spring adapted to embrace a pump-rod, means for suspending the spring, a 10 sleeve carried by the lower end of the spring and adapted to embrace the pump-rod, hangers depending from the sleeve and having spurs, a plate adapted to be secured to the pump-rod and having a series of holes to 15 receive said spur.

5. In combination with a pump-rod, a

helical spring embracing the pump-rod, means for suspending the upper end of the spring, a hanger depending from the lower end of the spring, and means for attaching 20 said hanger to the pump-rod.

6. In combination with a pump-rod and windmill tower, a helical spring embracing the pump-rod, means connecting the upper end of the spring with the tower, a hanger 25 pivoted to the lower end of the spring, a spur on the hanger, a plate secured to the pump-rod and having a series of holes to receive the spur of the hanger.

Witness my hand this 30 day of December, 1916.

GEORGE W. McCONNELL.
